Primary Examiner—Gary D. Watson*Assistant Examiner*—Susan Bennett Hattan(74) *Attorney, Agent, or Firm*—Moser, Patterson & Sheridan**CLAIM**

The ornamental design for a hangtag, as shown and described.

DESCRIPTION

FIG. 1 is a front perspective view of the hangtag.

FIG. 2 is a front elevational view of the hangtag.

FIG. 3 is a left side elevational view of the hangtag, the right side being a mirror image thereof.

FIG. 4 is a top plan view of the hangtag; and,

FIG. 5 is a bottom plan view of the hangtag.

The broken lines in FIGS. 1 through 5 are for illustrative purposes only and form no part of the claimed design.
